UNITED STATES PATENT OFFICE.

JOHN F. O'CONNOR, OF CHICAGO, ILLINOIS, ASSIGNOR TO WILLIAM H. MINER, OF CHAZY, NEW YORK.

RECORDING MECHANISM.

1,265,489.

Specification of Letters Patent.

Patented May 7, 1918.

Application filed January 31, 1916. Serial No. 75,320.

To all whom it may concern:

Be it known that I, JOHN F. O'CONNOR, a citizen of the United States, residing at Chicago, in the county of Cook and State of Illinois, have invented a certain new and useful Improvement in Recording Mechanism, of which the following is a full, clear, concise, and exact description, reference being had to the accompanying drawings, 10 forming a part of this specification.

This invention relates to improvements in recording mechanisms.

An object of the invention is; to provide a mechanism for recording sudden accelerations and decelerations in the movements of vehicles and, more particularly, railroad cars.

Another object of the invention is; to provide a mechanism of the character above indicated which will also produce a continuous record of the accelerations and decelerations and simultaneously indicate the intensity or extent thereof.

The invention furthermore consists in the improvement in the parts and devices and in the novel combination of the parts and devices herein shown, described or claimed.

For many years railroads and manufacturers of railway draft gears have been desirous of obtaining accurate information showing the exact service to which the draft gears are subjected in order to determine the relative efficiency and wearing qualities of different types of gears. Heretofore there has been no reliable means for recording either the number of shocks transmitted to the gear and from the latter to the car during a certain run or period of time nor the intensity of shocks, due to increasing speeds or decreasing the same in starting a train or stopping the same or in varying the speed while running. It has therefore been necessary to merely estimate the number of actions of the gears and practically no means whatsoever have been available to estimate the average intensity of the shocks, and from which the working performance or endurance of the gears could be estimated.

My invention contemplates means by which the above indicated desired data may be obtained.

In the drawing forming a part of this specification, Figure 1 is a top plan view of a mechanism embodying my improvements. 55 Fig. 2 is a side elevation of the structure

illustrated in Fig. 1. Fig. 3 is a horizontal, sectional view taken substantially on the line 3—3 of Fig. 2. Fig. 4 is a longitudinal, central, vertical, sectional view taken substantially on the line 4—4 of Fig. 1. Figs. 5 and 6 are vertical, transverse, sectional views taken substantially on the lines 5—5 and 6—6, respectively, of Fig. 2. Fig. 7 is a detail view illustrating the means employed for stopping and releasing the spring motor. And Fig. 8 is a diagrammatic view illustrating a record made with my improvements.

As shown, the improved recording mechanism comprises a rectangular bed or base plate A; a yieldingly controlled heavy block or member B, which is movable relatively to the member A, as hereinafter described; a uniformly movable record sheet C operated by a spring motor fixed with respect to the base plate A; and a marking instrumentality designated generally by the reference D, the latter being movable in unison with the slidable block B. The bed or base plate A is provided with a central, longitudinally extending recess 10 within which is adapted to reciprocate back and forth the depending portion of the preferably solid heavy block B, the latter being supported on a plurality of rollers 11—11 at the sides thereof, said rollers running in grooves or tracks 12—12 mounted on the base plate A. The heavy block B is provided with a centrally located recess 13 on its upper face and within which is mounted a spring 14, the latter being provided at its ends with spring followers 15—15 shaped on their outer faces to seat properly in corresponding grooves 16, at each end. The bed plate A is provided with upstanding brackets 17 in each of which is adjustably mounted a threaded rod 18 as by means of the set nuts 19—19, see Fig. 4. The rods 18—18 extend inwardly toward the center of the mechanism and pass through suitable perforations 20—20 in the member B, said rods 18 at their inner ends being tapered as indicated at 21 and fitting in correspondingly shaped recesses in the spring followers 15—15.

From the preceding, it will be seen that the member B may slide longitudinally of the member A in either direction from its normal central position and in this movement it is resisted by the spring 14. For

instance, if the member B moves to the left as the apparatus is viewed in Fig. 4, the left hand spring follower 15 remains stationary on the inner end of the left hand rod 18, and the right hand spring follower 15 is moved to the left by the member B, thus compressing the spring between it and the left hand follower 15. Similarly, the member B may move to the right in which case the right hand follower 15 is held by its corresponding rod 18 and the left hand follower 15 moves to the right, thus compressing the spring. At each end, the block B is suitably recessed as indicated at 22, in order to accommodate the adjacent set nuts 19 upon extreme movement of the block. The record sheet C unwinds from a roll 23 carried on a suitable rotatable cylinder 24, the sheet C passing over a horizontal table 25 and being wound around a second cylinder or drum 26. The drums or cylinders 24 and 26 are mounted on parallel shafts which are supported at their ends in two vertically arranged plates 27 and 28, each of said plates forming a bridge over the top of the block B and having depending legs 29-29 provided with feet 30-30 at the bottom thereof and by which the same are rigidly secured to the base plate A. The table 25 is provided at each end thereof with an undercut groove 31 to receive the edge of the sheet C as it travels thereover and properly guide the sheet. The two plates 27 and 28 are rigidly secured together by means of four longitudinally extending bolts 32 having spacer sleeves or bushings 33 mounted thereon between the plates. Said bolts 32 are also extended beyond the plate 28 and through an additional end plate or partition 34, the latter being properly spaced from the plate 28 by bushings 35 mounted on said bolts. Tightening nuts 36 are provided on the ends of the bolts. The space between the plates 28 and 34 accommodates a spring motor indicated most clearly in Figs. 1 and 6 and which I have designated generally by the reference E. Said spring motor is or may be of any well known or desired type and is governed by an escapement wheel 37 and pawl 38, see Fig. 6, the pawl being mounted on a shaft 39, see Fig. 7, which carries a disk 40 rotatable between two spring arms 41 which may be separated by rotating the finger cam 42. As will be understood, when the spring fingers 41 engage the disk 40, the spring motor is locked but may be released by merely turning the cam 42 and spreading the spring fingers and releasing the disk 40. The spring motor is geared to the winding drum 26 and, as will be understood, the sheet C is wound thereon at a constant speed which may be regulated to any desired rate.

The movable block B is provided at one end thereof with an upstanding forked

bracket 43 to which is pivoted a lever 44, the latter at its inner end being provided with an adjustable tension, pencil holder 45, the pencil being so located that in normal position of the parts it will engage the record sheet C substantially at the middle thereof. By means of the adjustable rods 18-18 it is apparent that the normal position of the block B may be adjusted so as to properly locate the pencil on the sheet C. The pencil is held in engagement with the sheet by its own weight and that of the lever 44. The record sheet is preferably marked as indicated in Fig. 8, that is, with a central, longitudinal line *a* and parallel uniformly spaced lines *b* on each side thereof, and transversely extending lines *c* which are also uniformly spaced. The sheet travels across the table 25 in the direction indicated by the arrow *x* in Fig. 8 and if movement of the member B relatively to the base plate A did not occur the pencil would make a line coinciding with the center line *a*. However, upon displacement of the member B from its normal position it will make a transverse line such as indicated at *d-d* of Fig. 8. The extent or intensity of the movements of the member B may be calculated from the lines *b-b* and the time at which they take place is determined by the spaces formed by the vertical lines *c-c*, the latter being spaced to accord with five minute intervals.

The apparatus is used as follows. Whenever it is desired to make a record, the apparatus is placed in the car or other vehicle and so arranged that the tracks 12-12 on which the member B slides, extend parallel with the line of movement of the car. The apparatus is of sufficient weight for all practical purposes to prevent slipping thereof relative to the car but of course it may be secured to the floor of the car by any suitable means if desired. Assuming the apparatus in place in the car and the clock work released so as to start the sheet C and the car to be moved toward the right as viewed in Figs. 3 and 4. As the car is given a sudden start, the bed plate, spring motor and record carrying sheet will, of course, move absolutely in unison therewith but the member B, which comprises a relatively heavy solid mass of metal, and being only under spring control, will tend to remain stationary. In other words, the member B will move toward the left hand end of the base plate A as viewed in Fig. 4, and will thus produce a line *d* which is below the horizontal line *a*. The extent of this relative movement will depend upon the intensity of the starting shock or acceleration. After the member B has been displaced from normal its maximum amount by the shock, it will return to normal and move a somewhat lesser amount in the opposite direction from normal, due to the recoil of the spring but

will then return to normal. Now assuming the apparatus in operation in a car which is moving at a comparatively high rate of speed and which has the brakes suddenly applied thereto, it is apparent that the heavy body B will, under its own momentum, continue to move forwardly at the same rate of speed so that it will be displaced relatively to the base plate A. This will cause the pencil to first make a transverse line *d* above the horizontal line *a* and its intensity will be indicated by the length of said line *d*.
 Inasmuch as it is not desirable to record every minute shock or change in speed of the moving vehicle, the spring 14 is made strong enough so that the member B will not be moved from normal position except by shocks heavier than a predetermined amount. The record shown in Fig. 8 is a sample record taken in a street car and shows the number and intensity of starts and stops of the car in a period of less than 10 minutes. As will be understood, the lines *d* are always practically straight lines perpendicular to the center line *a*, since the shocks of either starting or stopping are practically instantaneous and the sheet C moves at a comparatively slow rate.

By placing my improved apparatus in a car, the same may be made to produce an automatic record of a car either for any period of time or for any certain run, and it will show the number of times the car has been suddenly accelerated or decelerated and the intensity of each movement or shock, whereby accurate information may be obtained as to the actual conditions to which a draft gear or in fact any part of a car is subject.

I have herein shown and described specifically one embodiment of my improvement but it is obvious that the invention may be embodied in various other struc-

tures and arrangements without departing from the spirit of the invention, and I contemplate all such changes and modifications as come within the scope of the claims appended hereto.

When the apparatus is not in use, the slideable block B may be held in fixed position by the vertically slideable pin 46 which passes through said block and is adapted to enter a suitable recess in the base casting A. When in use the pin 46 is elevated to the position shown in dotted lines in Fig. 2 and may be held in such position by turning the pin so as to have the key 47 thereon rest upon the upper surface of the block B.

I claim:

1. In a recording mechanism of the character described, the combination with a base plate, of a member slidably mounted on said base plate, said member having a central recess, a spring mounted within said recess, followers coöperating with said spring and said member, means for preventing movement of each of said followers in one direction, and automatically operated means for recording movement of said member relatively to the base plate.

2. In a recording mechanism of the character described, the combination with a base plate, of a member slidably mounted on said base plate, said member having a recess therein, a spring mounted within said recess, followers within said recess and coöperating with said spring and said member, means for preventing movement of each of said followers in one direction, said means being adjustable, and automatically operated means for recording movements of said member relatively to the base plate.

In witness that I claim the foregoing I have hereunto subscribed my name this 28th day of January, 1916.

JOHN F. O'CONNOR.
